Specification for Design.

Patented Jan. 3, 1922.

Application filed October 15, 1920. Serial No. 417,243. Term of patent 14 years.

To all whom it may concern:

Be it known that we, GEORGE K. THOMPSON and ALFRED U. HARPER, citizens of the United States, residing at Maplewood, in the county of Essex and State of New Jersey, and Evanston, in the county of Cook and State of Illinois, respectively, have invented a new, original, and ornamental Design for Hand Telephones, of which the following is a specification, reference being had to the accompanying drawing, forming a part thereof.

The drawing is a perspective view of a hand telephone, showing our new design.

We claim:

The ornamental design for a hand telephone, as shown.

In testimony whereof, we have signed our names to this specification, this 13th and 6th day of October, 1920.

GEORGE K. THOMPSON.
ALFRED U. HARPER.
